United States Patent Office

Des. 227,037

Patented May 29, 1973

227,037

PEN

Harold F. Bajusz, Woodridge, N.J., assignor to Accufec Inc., Wallington, N.J.

Filed May 14, 1971, Ser. No. 143,729

Term of patent 14 years

Int. Cl. D19—06

U.S. Cl. D74—17 B

FIG. 1 is a front elevation view of a pen showing my new design as it appears with the cap covering the pen portion;

FIG. 2 is a side elevation view thereof as it appears with the cap removed therefrom;

FIG. 3 is a top plan view of the barrel portion of the pen disclosed in FIG. 2; and

FIG. 4 is a bottom plan view thereof.

I claim:

The ornamental design for a pen, as shown.
